UNITED STATES PATENT OFFICE.

LUCY H. GAINES, OF CHATTANOOGA, TENNESSEE.

DESIGN FOR A GAME-BOARD.

SPECIFICATION forming part of Design No. 34,985, dated August 20, 1901.

Application filed July 18, 1901. Serial No. 68,852. Term of patent 14 years.

To all whom it may concern:

Be it known that I, LUCY H. GAINES, a citizen of the United States, residing at Chattanooga, in the county of Hamilton and State of Tennessee, have invented and produced a new and original Design for a Game-Board, of which the following is a specification.

This invention relates to a new and original design for a game-board; and the essential features reside in the design as illustrated in the accompanying drawing, which shows a plan view of the game-board embodying the design.

The numeral 1 designates a square board having lines 2 at a distance inwardly from and parallel with the side edges thereof and intersecting at the extremities to form corner-squares 3, in which are colored stars 4. Between the lines 2 and the edges of the board are a plurality of parallel short lines 5 at right angles to said edges and lines 2. The lines 2 inclose a space 6, having a central field in the

form of a square 7, with rounded corners 8, and having inner lines 9 parallel with the outer lines of said square 7 and connected by shorter lines 10 at an angle thereto and which radiate at the corners from central colored bars 11, which are diagonally disposed. The lines 9 of the square 7 also inclose a space having concentric circles 12 in the center thereof, lines 13 radiating from a central blank space 14 to the inner circle.

Having thus described the invention, what is claimed as new is—

The design for a game-board, as herein shown and described.

In testimony that I claim the foregoing as my own I have hereto affixed my signature in the presence of two witnesses.

LUCY H. GAINES.
